(57) **CLAIM**

The ornamental design for a carrier, as shown and described.

DESCRIPTION

FIG. 1 is an upper perspective view of a carrier from a first end thereof, showing a handle and mounting component of the carrier retracted, and showing a retainer of the carrier in an inoperative position;

FIG. 2 is an upper perspective view of the carrier of FIG. 1 from the first end, showing the handle and mounting component of the carrier extended;

FIG. 3 is a lower perspective view of the carrier of FIG. 1 from a second end thereof, the second end being opposite the first end;

FIG. 4 is a plan view of the carrier of FIG. 1;

FIG. 5 is a bottom view of the carrier of FIG. 1;

FIG. 6 is an elevation view of the carrier of FIG. 1 from a first side thereof;

FIG. 7 is an elevation view of the carrier of FIG. 1 from a second side thereof, the second side being opposite the first side;

FIG. 8 is an elevation view of the carrier of FIG. 1 from the first end;

FIG. 9 is an elevation view of the carrier of FIG. 1 from the second end;

FIG. 10 is an upper perspective view showing the carrier on FIG. 1 in which the handle and mounting component are retracted and the retainer is in an operative position; and, FIG. 11 is an upper perspective view showing the carrier in which the handle and mounting component are extended and the retainer is in the inoperative position.

The broken lines in FIGS. 10 & 11 depict balls representing the environment of the carrier and form no part of the claimed design.
